ANTICIPATOR APPARATUS

Anthony F. Schwendner, Ridley Park, Pa., assignor to Westinghouse Electric & Manufacturing Company, East Pittsburgh, Pa., a corporation of Pennsylvania

Application September 8, 1939, Serial No. 293,883

10 Claims. (Cl. 175—294)

My invention relates to a power plant comprising a prime mover driving a generator connected to an electrical system and it has for an object to provide anticipating apparatus responsive to sudden load drop to close the prime mover admission valve to prevent overspeeding of the prime mover to such an extent that the emergency governor would be operated to close the throttle valve, the prime mover governing mechanism regaining control of the admission valve at the lower speed level.

In Griscom et al. Patent No. 2,000,753, May 7, 1935, and assigned to the Westinghouse Electric & Manufacturing Company, there is disclosed and claimed apparatus of the watt-meter type which operates in an anticipatory manner to close the prime mover admission valve in case of sudden load drop to prevent overspeeding sufficient to operate the emergency governor and trip the throttle valve for closing. While this apparatus may be timed to permit the governor to regain control of the turbine at the lower load level, it is desirable to supplement the performance of this function by hydraulic means, which, in response to sudden load drop, furnishes fluid pressure which supersedes the governor in control of the admission valve and brings about closing of the latter and which, independently of the watt-meter device, provides for release of the anticipating fluid pressure after a predetermined time interval. Accordingly, a further object of my invention is to provide a hydraulic anticipating apparatus responsive to sudden load drop for furnishing anticipating pressure to supersede the governor in control of the admission valve in order to close the latter, the anticipating apparatus including means providing for release of the anticipating pressure after a predetermined short time interval in order that the governor may regain control of the admission valve at the lower load level.

These and other objects are effected by my invention as will be apparent from the following description and claims taken in connection with the accompanying drawing, forming a part of this application, in which:

The figure is a longitudinal sectional view of a prime mover having my improved control mechanism applied thereto.

Referring to the drawing more in detail, there is shown an electrical system including the leads 10 of the generator 11 driven by the turbine 12 having an admission valve 13 and a throttle valve 14. As is well known in the art and as shown on the drawing, the throttle valve is normally

held open by fluid pressure acting on a piston 15 and opposed by a spring 16, the fluid pressure being relieved in the event of overspeeding of the turbine by means of emergency governing mechanism, at 17, so that the spring or biasing means 16 is effective to close the throttle valve quickly. The present invention is concerned with governing mechanism, at 18, which normally controls the admission valve 13 and anticipating apparatus, at 19, which supersedes the governor in control of the admission valve in case of sudden load drop.

Preferably, the governing mechanism, at 18, and the anticipating apparatus, at 19, exert their controlling effects on the servo-motor, at 20, which operates the admission valve 13.

Referring first to the servo-motor, this includes an operating cylinder 21 with an operating piston 22 therein, the operating piston having a stem 23 whose upper end is connected by means of the lever 24 to the admission valve 13. Motive fluid is admitted and exhausted to opposite ends of the operating cylinder by means of a pilot valve 25.

The governing and anticipating impulses or pressures are preferably not used directly to move the pilot valve 25 but to control motive means for effecting movements thereof. The motive means for this purpose includes a spring 26 acting upwardly against the lower end of the pilot valve and fluid pressure in the chamber 27 and whose force acts downwardly on the upper end of the valve. Fluid under pressure is supplied to the chamber through a restricted orifice 28 and it escapes from the chamber through the annular orifice defined by the cup valve 29 and the upper end of the pilot valve and then passes through the drain passage 31 formed in the latter.

With this arrangement, if the cup valve 29 is moved upwardly, pressure in the chamber 27 is reduced, the supply being restricted by the orifice 28, and the spring 26 causes the piston valve to follow the cup valve. On the other hand, if the cup valve 29 is moved downwardly, thereby restricting the annular orifice area, the pressure builds up in the chamber 27 and causes the piston valve 25 to move downwardly. Thus, it will be seen, that the disturbance of fluid pressure in the chamber 27 brought about by movement of the cup valve is ensued by following movement of the piston valve in order to reestablish equilibrium of forces acting thereon.

The relay or cup valve 29 is operated by pressure-responsive means, at 32, subject to govern-

ing and hydraulic pressures as will be hereinafter pointed out.

The pressure-responsive means, at 32, is comprised by a chamber 33 formed in the housing structure 34, the chamber having the smaller and larger bellows 35 and 36 therein, the upper end of the smaller and the lower end of the larger bellows being attached to the structure 34 and the adjacent ends being connected to the movable abutment 38 presenting the annular pressure abutment or piston area 39. Thus, it will be seen that the bellows 35 and 36, the movable abutment 38, and interior walls of the chamber 33 provide a pressure chamber to which fluid under pressure is admitted from the governing mechanism, at 18, and the anticipating apparatus, at 19, the chamber having a small vent 41 for the escape of trapped air and gases.

The governing mechanism, at 18, and the anticipating apparatus, at 19, have fluid passages 43 and 44 for furnishing fluid under regulating and anticipating pressures, respectively, to the pressure chamber 33 of the pressure-responsive device, at 32, pressure changes being applied to the pressure abutment 38 connected, by means of the stem 45, to the cup valve 29. If there is an increase in pressure to the chamber 33, the cup valve 29 is moved downwardly, bringing about downward movement of the pilot valve 25, upward movement of the operating piston 22 and movement in a closing direction of the admission valve 13. If the pressure decreases, movements take place in the opposite direction and the admission valve 13 is opened wider.

Movement of the operating piston 22 is also utilized by the follow-up mechanism, including the lever 46 and the link spring 47 between the lever and the upper end of the stem 45, to restore the cup valve 29 to such a position that the pilot valve 25 will be brought to neutral to terminate movement of the operating piston 22 and the admission valve, that is, assuming a change in load and a consequent change in regulating pressure supplied by the passage 43 to the chamber 33, with movements of the piston valve, the operating piston, and the admission valve, as just pointed out, such movements occur with change in the force of the spring 47 and they will continue until the force of the latter is in equilibrium with the force of the changed fluid pressure acting on the abutment 38 with the cup valve 29 in a position corresponding to neutral of the piston valve in order to terminate valve-adjusting operation.

The fluid pressure passages 43 and 44 are connected, by automatic valve means, to the pressure chamber 33, such valve means providing for communication of the passage of higher pressure with such chamber. As shown, the valve means is comprised by an elongated chamber 51 whose upper and lower ends communicate with the passages 43 and 44 and whose intermediate portion is connected, by means of the passage 52, with the pressure chamber 33 and a ball valve 53 is arranged in the elongated chamber. With this arrangement, it will be apparent that, in the absence of pressure supplied to the passage 44, or if the pressure in the passage 44 is below the regulating pressure furnished by the governor, at 18, to the passage 43, the ball valve 53 will occupy its lowermost position, closing the discharge end of the passage 44 and effecting communication between the passage 43 and 52; on the other hand, if anticipating

pressure is developed, such pressure being normally substantially greater than the maximum regulating pressure, the ball valve will be lifted, interrupting communication of the passage 43 with the chamber 33 and placing the passage 44 in communication with the latter chamber, whereby the relatively large anticipating pressure acts on the pressure-responsive relay, at 32, to render the servo-motor, at 20, effective to close the admission valve 13.

Referring now to the governor, at 18, for furnishing fluid under regulating pressure to the passage 43, this is preferably of the pressure transformer type, that is, it responds to a primary or controlling force dependent on prime mover speed to provide a regulating pressure having definite relation with respect thereto. For example, the means for securing the primary or controlling force is shown as comprising a pressure chamber 55 defined in part by the movable abutment 56 and the bellows 57 and to which fluid under pressure varying substantially as the square of the speed of the prime mover turbine is supplied from the reverse-flow impeller, at 58, the force of such pressure acting on the abutment 56 against the force of the spring 59 whose tension may be adjusted by the speed changer 60.

A member 61 has its lower end arranged in abutting relation with respect to the abutment 56 and it cooperates with suitably arranged ports to provide the regulating pressure. For example, the member 61 may take the form of a spinner piston, the spinner piston valve having spaced lands 62 and 63 fitting in the cylinder 64 and normally just lapping pressure and exhaust ports 65 and 66, respectively, so as to interrupt communication thereof with the regulating pressure port 67, the regulating pressure port communicating with the conduit or passage 43 and also communicating, by way of the branch passage 68, with the upper end of the cylinder 64 so that regulating pressure acts on the upper piston area 69 provided by the upper land 62.

With this arrangement, if there is a change in speed, the governing pressure supplied to the chamber 55 changes and the abutment 56 moves to move the spinner piston valve; however, just as soon as the latter moves a very slight amount, depending upon the direction of movement, either the pressure port 65 or the drain port 66 is placed in communication with the regulating pressure port 67 to increase or decrease the regulating pressure and the regulating pressure will change until the force thereof acting on the piston area 69 may restore the spinner piston valve to neutral position, that is, until the force of regulating pressure acting on the piston area 69 is brought into equilibrium with the force of governing pressure acting on the piston area 56, a change in governing pressure being accompanied by a relatively larger change in regulating pressure in the ratio of the area 56 to the area 69.

Referring now to the anticipating device, at 19, responsive to a predetermined rate of change in decline or drop in load, the generator outlet leads 10 have associated therewith a watt-meter control device 72 of well-known construction, such as shown and described more in detail in said patent to Griscom et al., which serves to open and to close the D. C. circuit 73 including the winding 74, the operation being such that the circuit is closed when the rate of change of decline in load of the generator exceeds a

predetermined value; and, if such rate of change is sufficiently great, as in the case of load drop, then the D. C. circuit is closed and the winding or solenoid 14 is energized to pull the core 15 downwardly for the purposes to be immediately described.

The core 15 is connected to a lever 16 having one end fulcrumed, at 17, and its other end pivoted, at 18, to the upper end of the rod 19 connected to the piston valve 80 in the piston valve cylinder 81 of the body 82. A spring 83 exerts an upward force on the rod 19 opposing the downward magnetic pull of the solenoid 14. The structure 82 has a port 84 communicating with the cylinder 81 and connected to the pressure supply line 85 and with a port 86 spaced a suitable distance from the port 84 and communicating with the drain passage 87.

The structure 82 also has a port 88 having one end communicating with the cylinder 81 between the ports 84 and 86 and having its other end communicating with the lower annular enlargement 89 of the piston valve cylinder 90, the piston valve cylinder having an intermediate enlargement 92 arranged above the enlargement 89 and a top enlargement 93. The lower end of the piston valve cylinder 90 communicates with the cylinder 94.

A piston 95 is arranged in the cylinder 94 and it is connected to a piston valve 96 having upper and lower lands 97 and 98. A spring 99 acts downwardly on the piston 95 to move the latter and the piston valve downwardly if unopposed. The passage 88 is connected by a branch passage 100 with the space of the cylinder below the piston 95, the passage having an adjustable orifice 101.

In the event of generator load drop, the solenoid 14 pulls the piston valve 80 to place the pressure supply port 84 in communication with the passage 88; and, with the piston valve 96 in the position shown, fluid will pass from the lower enlargement 89 to the intermediate enlargement 92 and then past the check valve 102 to the passage 44, the anticipating pressure so developed superseding the regulating pressure and causing the servo-motor, at 20, to close the admission valve.

Just as soon as anticipating pressure is applied in the passages 88 and 44 in this manner, it is also effective in the passage 100 and gradually builds up in the cylinder 94 beneath the piston 95, as determined by the setting of the orifice 101, the effect of pressure building up underneath the piston 95 being to move the piston valve 96 upwardly until the land 98 interrupts communication of the enlargement 89 with the enlargement 92, whereupon, due to cut-off of the passage 44 from the passage 88, the supply of pressure to the passage 44 is terminated and the regulating pressure furnished by the governing mechanism, at 18, regains control of the pressure-responsive servo-motor, at 20.

When the rate of change declines to a predetermined small or zero value, that is, when the lower load level is reached, the spring 83 moves the pilot valve 80 back to its normal position shown on the drawing, and, in which position, it interrupts communication of the pressure port 84 with the passage 88.

The pilot valve 80 has a bore 105 and radial ports 106 providing for the escape of oil accumulating in the lower end of the cylinder 81 and which would otherwise impede movement of

the pilot valve. Also, the upper circumferential enlargement space 93 provides for drainage of oil from about the upper end of the piston valve 96 through the passage 107 and the ports 106 to the drain port 86.

The operation of the apparatus described is as follows: Normally, the governing mechanism, at 18, provides a regulating pressure or force range for the prime mover, the regulating pressure or force acting on the pressure-responsive servo-motor, at 20, to control the position of the admission valve 13, so that, with an increase in load, opening of the valve is increased and vice versa. In the event of sudden load drop such that the governing mechanism, at 18, would not move the admission valve 13 in a closing direction quick enough to prevent overspeeding of the turbine 12 and consequent tripping of the emergency governing apparatus, resulting in stoppage of the turbine and requiring restart of the latter and reconnection of its generator to the line, the anticipating apparatus, at 19, is employed to close the admission valve 13 just as soon as a predetermined rate of change or decline in load drop occurs. The watt-meter device 72 responds immediately to load drop, bringing about completion of the D. C. circuit 13 to provide an anticipating force which supersedes the governing force and closes the admission valve. Preferably, the circuit 73, when closed, energizes the solenoid 14, in consequence of which the device, at 19, is rendered effective to supply fluid under anticipating pressure through the passage 44 to the lower end of the valve chamber 51, such pressure moving the ball valve 53 upwardly and entering the pressure chamber 33 to render the servo-motor, at 20, effective to close the admission valve.

Means is provided to limit duration of the anticipating force so that restoration of the prime mover to control by the governing force may not be delayed too long. This result is preferably accomplished by the hydraulic timing arrangement forming a part of the device, at 19. As soon as the pressure source is placed in communication with the anticipating pressure passage including the passages 88 and 44, to supply fluid under anticipating pressure to the chamber 33 to close the admission valve 13, such pressure is also supplied through the branch passage 100 and the adjustable orifice 101 to the cylinder space below the piston 95, the latter moving upwardly at a speed determined by the setting of the orifice 101. As soon as the piston valve 96 moves a sufficient distance that the lower land 98 interrupts communication of the passages 88 and 44, then, irrespective of the condition or position of the watt-meter device 72 and the piston valve 80, the supply of fluid under anticipating pressure to the pressure-responsive device, at 32, will cease, the bleeder port 41 for venting the pressure chamber 33 of air and gases providing slow leakage or bleeding of liquid so that the pressure in the passage 44 declines rapidly and the governing mechanism, at 18, regains control of the turbine. Not only may the orifice 101 be adjusted to time the anticipating apparatus, at 19, so that the governing mechanism, at 18, regains control of the turbine with the desired degree of rapidity, but this orifice is also useful in case of load surges, the orifice being adjusted so that in case of a predetermined rate of change of load, the admission valve is closed and again reopened at a

suitable time in relation to electrical characteristics of the system so as to minimize surges.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. The combination with an electric generator driven by a prime mover and the prime mover having an admission valve, of pressure-responsive means for operating the admission valve; a governor providing a regulating pressure varying as a function of speed of the prime mover; means responsive to sudden generator load drop to provide an anticipating impulse; means responsive to the anticipating impulse to provide an anticipating fluid pressure; means effective, when fluid under regulating pressure is developed and there is absence of fluid under anticipating pressure, to supply fluid under regulating pressure to the pressure-responsive means to control the admission valve in accordance with the load and effective, when fluid under anticipating pressure is developed, to supply the latter to the pressure-responsive means to effect movement of the admission valve in a closing direction; and means responsive to initiation of supply of fluid under anticipating pressure for terminating the latter a predetermined time interval after it becomes effective.

2. The combination with an electric generator driven by a prime mover and the prime mover having an admission valve, of pressure-responsive means for operating the admission valve; a governor providing a regulating pressure varying as a function of speed of the prime mover; means responsive to sudden generator load drop to provide an anticipating impulse; means responsive to the anticipating impulse to provide an anticipating fluid pressure; means effective, when fluid under regulating pressure is developed and there is absence of fluid under anticipating pressure, to supply fluid under regulating pressure to the pressure-responsive means to control the admission valve in accordance with the load and effective, when fluid under anticipating pressure is developed, to supply the latter to the pressure-responsive means to effect movement of the admission valve in a closing direction; means responsive to fluid under anticipating pressure for terminating the supply of the latter to the pressure-responsive means; and means for varying the time required for the last-named means to act.

3. The combination with an electric generator driven by a prime mover and the prime mover having an admission valve, of pressure-responsive means for operating the admission valve; a governor providing a regulating pressure varying as a function of speed of the prime mover; means responsive to sudden generator load drop to provide an anticipating impulse; means responsive to the anticipating impulse to provide an anticipating fluid pressure; means effective, when fluid under regulating pressure is developed and there is absence of fluid under anticipating pressure, to supply fluid under regulating pressure to the pressure-responsive means to control the admission valve in accordance with the load and effective, when fluid under anticipating pressure is developed, to sup-

ply the latter to the pressure-responsive means to effect movement of the admission valve in a closing direction; means responsive to fluid under anticipating pressure for terminating the supply of the latter to the pressure-responsive means; means including an orifice for supplying fluid under anticipating pressure to the last-named means; and means providing for variation in the flow area of the orifice.

10. 4. The combination with an electric generator driven by a prime mover and the prime mover having an admission valve, of pressure-responsive means for operating the admission valve, a governor providing a regulating pressure varying as a function of speed of the prime mover, means responsive to sudden generator load drop to provide an anticipating impulse, means responsive to the anticipating impulse to provide an anticipating fluid pressure, means for supplying fluid under regulating and anticipating pressures to the pressure-responsive means and including a valve responsive to regulating pressure when the anticipating pressure is ineffective so that fluid under regulating pressure may be supplied to the pressure-responsive means and responsive to anticipating pressure so that the latter may be supplied to the pressure-responsive means, and means responsive to initiation of supply of fluid under anticipating pressure for terminating the latter a predetermined time interval after it becomes effective.

5. The combination with an electric generator driven by a turbine and the turbine having an admission valve, of pressure-responsive means for operating the admission valve, a governor providing a regulating pressure varying as a function of speed of the prime mover, means responsive to sudden generator load drop to provide an anticipating impulse, means responsive to the anticipating impulse to provide an anticipating fluid pressure, first and second conduits for supplying fluid under regulating and anticipating pressures, respectively, to the pressure-responsive means, valve means responsive to regulating pressure when the anticipating pressure is ineffective to connect the first conduit to the pressure-responsive means and responsive to anticipating pressure to connect the second conduit to the pressure-responsive means, a normally-open valve movable to interrupt the supply of fluid under anticipating pressure to the second conduit, and timing means rendered effective upon establishment of fluid under anticipating pressure for controlling the duration of time interval required for closing of the last-named valve.

6. The combination with an electric generator driven by a turbine and the turbine having an admission valve, of pressure-responsive means for operating the admission valve, a governor providing a regulating pressure varying as a function of speed of the prime mover, means responsive to sudden generator load drop to provide an anticipating impulse, means responsive to the anticipating impulse to provide an anticipating fluid pressure, first and second conduits for supplying fluid under regulating and anticipating pressures, respectively, to the pressure-responsive means, valve means responsive to regulating pressure when the anticipating pressure is ineffective to place the first conduit in communication with the pressure-responsive means and to interrupt communication with the latter of the second conduit and responsive to anticipating pressure to interrupt communica-

tion of the first conduit with the pressure-responsive means and to open communication of the second conduit with the latter, a normally-open valve movable to interrupt the supply of fluid under anticipating pressure to the second conduit, means for biasing the valve to open position, a piston connected to the valve, and means including an adjustable orifice for supplying fluid under anticipating pressure for action on the piston in opposition to the biasing means to overcome the latter and close the valve.

7. The combination with an electric generator driven by a turbine and the turbine having an admission valve, of pressure-responsive means for operating the admission valve such that increases in pressure supplied thereto move the valve in a closing direction and vice versa, a governor providing a regulating pressure varying as a function of speed of the prime mover, means responsive to sudden generator load drop to provide an anticipating impulse, means responsive to the anticipating impulse to provide an anticipating fluid pressure which is larger than the maximum regulating pressure, first and second conduits for supplying fluid under regulating and anticipating pressures, respectively, to the pressure-responsive means, valve means responsive to regulating pressure when the anticipating pressure is ineffective to open communication of the first conduit with the pressure-responsive means and to interrupt communication of the second conduit with the latter and responsive to regulating pressure to open communication of the second conduit with the pressure-responsive means and to interrupt communication of the first conduit with the latter, a normally-open piston valve having a range of movement to interrupt the supply of fluid under anticipating pressure to the second conduit, a spring for biasing the piston valve to open position, a piston connected to the piston valve, and means including an adjustable orifice for supplying fluid under anticipating pressure for action on the piston in opposition to the spring to close the piston valve.

8. The combination with an electric generator driven by a turbine and the turbine having an admission valve, of pressure-responsive means for operating the admission valve such that increases in pressure supplied thereto move the valve in a closing direction and vice versa, a governor providing a regulating pressure which increases with decrease in load and vice versa, means including a control circuit and a wattmeter device responsive to sudden generator load drop to close the control circuit, means energized by electric current flowing in the control circuit to provide an anticipating fluid pressure which is larger than the maximum regulating pressure, first and second conduits for supplying fluid under regulating and anticipating pressures, re-

60 spectively, to the pressure-responsive means, valve means responsive to regulating and anticipating pressures to establish communication of the first conduit with the pressure-responsive means when the anticipating pressure is ineffective and to establish communication of the second conduit with the pressure-responsive means when the anticipating pressure is effective, and means responsive to the initiation of supply of fluid under anticipating pressure for terminating the latter a predetermined time interval after it becomes effective.

9. The combination with an electric generator connected to an electrical system and driven by a turbine having an admission valve, of governor mechanism providing a regulating pressure which increases with increase in turbine speed and decrease in load and vice versa; means responsive to a predetermined rate of change of generator load to provide an anticipating pressure; pressure-responsive means for controlling the admission valve such that with an increase in pressure the valve is moved in a closing direction and vice versa; connections for supplying fluid under regulating and anticipating pressures to the pressure-responsive means so that normally the latter is operated in accordance with the magnitude of regulating pressure and, when the anticipating pressure becomes effective, it is operated to close the admission valve; and means rendered effective by the anticipating pressure to limit duration of action of the latter on the pressure-responsive means in order that the regulating pressure may regain control of the latter.

10. The combination with an electric generator connected to an electrical system and driven by a turbine having an admission valve, of governor mechanism providing a regulating pressure which increases with increase in turbine speed and decrease in load and vice versa; means responsive to a predetermined rate of change of generator load to provide an anticipating pressure; pressure-responsive means for controlling the admission valve such that with an increase in pressure the valve is moved in a closing direction and vice versa; connections for supplying fluid under regulating and anticipating pressures to the pressure-responsive means so that normally the latter is operated in accordance with the magnitude of regulating pressure and, when the anticipating pressure becomes effective, it is operated to close the admission valve; means rendered effective by the anticipating pressure to limit duration of action of the latter on the pressure-responsive means in order that the regulating pressure may regain control of the latter; and means for adjusting the last-named means to vary the duration of action of the anticipating pressure.

ANTHONY F. SCHWENDNER.
